ATTORNEY

UNITED STATES PATENT OFFICE.

JAMES W. BONTA, OF PHILADELPHIA, PENNSYLVANIA, ASSIGNOR TO THE AMERICAN NATIONAL TELEPHONE COMPANY, OF NEW YORK.

TELEPHONE TRANSMITTER.

SPECIFICATION forming part of Letters Patent No. 365,778, dated July 5, 1887.

Application filed December 21, 1886. Serial No. 222,180. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 Figures 1 and 2 are vertical sections of telephonic transmitters embodying my improvements.

My invention has relation to telephonic transmitters having carbon or analogous electrodes; and it has for its object simplicity of construction for maintaining efficient initial contact for the electrodes and for varying their contact-pressure.

My invention accordingly consists of the combination, construction, and arrangement of parts, as hereinafter described and claimed, having reference particularly to an electrode contacting with the diaphragm, which is either fixed or hinged, a loose or moving pivotal connection for the electrode, which connection is located below the body or mass of the electrode, and spring-pressure devices having tension mechanism whose lines of force approximate a right angle for giving an initial contact to the electrodes and for varying the same.

In the drawings, A represents a suitable box or casing having a removable cap, a, mouth-piece a', and diaphragm B, which is either fixed, as shown in Fig. 1, and provided with an electrode, b, or is hinged to the casing A, as indicated at b', Fig. 2, in which case it is preferably a carbon plate, and the electrode C contacts directly therewith.

10 The electrode C is attached to a right-angled bar, c, which is pivoted at c' in a bracket, D. The pivoted connections or bearings are preferably slots in bracket D, as shown at d, to provide for a movement of electrode C to the diaphragm. The pivot of electrode C is located below it, so that its gravity tends to move it toward the diaphragm.

To bar c is attached a vertical bar or plate spring, E, and a corresponding horizontally-

arranged spring, F, the point of attachment 50 of both springs E and F to bar c being the same, as shown.

The spring E has a tension-screw, e, in a bracket, e', secured to casing A, which tension-screw is located back of the spring, near 55 its upper end, and is adjusted to cause the latter to act to press the electrode toward the diaphragm.

Spring F has a tension-screw, f, in a bracket, f', affixed to casing A, and this tension-screw 60 is above the spring F, which imparts an upward pressure to electrode C for keeping it in its normal or contacting position with the diaphragm or its electrode b.

The combined effect of these described tension-spring devices for electrode C is to keep it in contact with the diaphragm, and by adjusting tension-screws e and f any degree initial contact may be obtained and varied, as desired. The electrodes are in the primary 1 of 70 an inductorium, I, in which primary is a battery, 2, and the secondary 3 of the inductorium forms part of the line.

What I claim is—

1. In a telephonic transmitter, a diaphragm-electrode, an electrode, C, attached to a right-angled arm or bar, c, having loose pivotal connections below the electrode, a vertical spring, E, a horizontal spring, F, having a common point of attachment to arm c, and 75 tension devices for said springs, substantially as set forth.

2. In a telephonic transmitter, a hinged carbon-plate diaphragm, an electrode, C, in contact with said diaphragm, a right-angled bar 85 or arm attached to electrode C and loosely pivoted below the latter, a vertical plate-spring and a horizontal plate-spring attached to said pivoted bar or arm, and tension devices for said springs, substantially as set 90 forth.

In testimony whereof I affix my signature in presence of two witnesses.

JAMES W. BONTA.
